GRINDING DISK SEGMENT FOR WOOD CHIPS
AND THE LIKE

Eric Kollberg, Harrison, Emil Moffa, Bronx, Hans Larsen, White Plains, and Thor Johansen, Nanuet, N.Y., assignors to American Defibrator Inc., New York, N.Y., a corporation of New York

Filed May 25, 1962, Ser. No. 197,744
1 Claim. (Cl. 241—298)

This invention relates to grinding disks of the character employed in an apparatus for grinding or defibrating wood chips or similar materials, and one of the objects of the invention is to provide a grinding surface for such disks which will materially improve the grinding operation.

Grinding disks as employed in defibrators are usually provided with a plurality of arcuately-shaped segments arranged end-to-end around the outer portion of the disks, and which segments are provided with ribbed grinding faces. The chips to be ground are delivered to the center of the grinding disks where they are thrown outward by the centrifugal force imparted to them by the vanes of the rotating segment holder. The actual fiber separation takes place as the steam-softened chips pass between the grinding segments. The fiber separation is materially affected by the design of the grinding faces of the segments and the present invention relates to a new and improved grinding face for the segments and by which improved results, with less wear on the grinding faces, results.

At the present time, grinding segments as used, exhibit a tendency to wear away faster adjacent to the periphery of the grinding disk due to the high velocity, with inside concentrated metal wearing away more slowly. As a result, a V-shaped opening develops from the outside of the segments toward the inner portion, which results in poor defibration. It is an object of the present invention to provide a grinding disk face in which the rapid wear, as above described, will be materially reduced.

It has also been noted that in grinding disks of known construction, and after the segments thereof have been in operation for 500 to 600 hours, a concentric groove tends to develop in the segments on one of the disks while a corresponding ridge develops in the segments on the companion disk. As a result, the passage of the material through the segments is slowed down and the useful life of the segments materially reduced. It is an object of the invention to provide segments in which the above occurrence is minimized; by which a more satisfactory grinding performance is obtained and a more uniform type of fiber is secured and longer life obtained for the segments with an improvement in power consumption.

More particularly, the invention contemplates the provision of an arcuately-shaped grinding segment having a plurality of spaced transverse ribs on its operative face defining grooves between them and extending obliquely across the segment, said spaces or grooves being bisected and interrupted at intervals by a plurality of cross ribs constituting barriers or dams arranged in staggered relation.

With these and other objects to be hereinafter set forth in view, we have devised the arrangement of parts to be described and more particularly pointed out in the claim appended hereto.

In the accompanying drawings, wherein an illustrative embodiment of the invention is disclosed,

FIG. 1 is a face view of a grinding disk segment, constructed in accordance with the invention;

FIG. 2 is an enlarged sectional view taken substantially on the line 2—2 of FIG. 1, looking in the direction of the arrows;

2

FIG. 3 is a rear view of the segment;

FIG. 4 is a face view of another embodiment of the invention;

FIG. 5 is a sectional view, taken substantially on the line 5—5 of FIG. 4, looking in the direction of the arrows;

FIG. 6 is a face view of another embodiment of the invention;

FIG. 7 is a sectional view, taken substantially on the line 7—7 of FIG. 6, looking in the direction of the arrows, and

FIG. 8 is a sectional view, taken substantially on the line 8—8 of FIG. 6, looking in the direction of the arrows.

In a defibrator or similar grinding apparatus, a pair of 15 facially-opposed grinding disks are employed, one and sometimes both, of said disks being rotated. The arcuate segments, three of which are shown in the accompanying drawings, provide the grinding surfaces on the disks and the same are mounted in end-to-end arrangement thereon 20 to form the annular grinding face.

Referring to the drawings, and more particularly to FIGS. 1 to 3 inclusive, there is disclosed a grinding disk segment in the form of an arcuate plate or casting 1, the outer or peripheral edge of the same being indicated 25 at 2 and its inner edge being shown at 3.

The grinding area of the disk segment is formed with a plurality of relatively closely spaced, obliquely extending ribs 4 having intervening lengthy grooves 5 between them. In the outer area of the segment, or that area which 30 extends inwardly from the periphery 2 for about one-half the width of the segment, the ribs 4 are of substantially uniform width and depth, the grooves 5 between them being alike as to width and depth. The area above mentioned, and defined by the ribs 4 and the intervening grooves 5 is 35 the grinding area which reduces the wood chips or other material to the required state of defibration.

Inwardly of the grinding area, as defined by the ribs and grooves above mentioned, the grooves widen and deepen, these wider and deeper parts being indicated at 40 6, so that inner portions 7 of the ribs 4 taper and incline at the top, as indicated at 8 in FIG. 2. The area in which the widened grooves are located constitutes the feeding area.

Extending between and connecting the ribs 4 and directed tangentially to the periphery of the segment is a 45 plurality of cross ribs 10 which cross ribs bisect and thus serve to interrupt the continuity of the transverse grooves 5 and form barriers or dams which extend angularly across the grinding area. Each of these barriers or dams extends inwardly at an angle from the periphery of the segment and each has its inner end 11 terminating at about the longitudinal center line of the grinding area of the segment. It will be noted that in this embodiment of the invention, the inner end 11 of each of the cross ribs 50 10 terminates at a point on a line extending radially of the segment at which point the beginning of the adjacent cross rib at the periphery of the segment is located. As will be clearly seen in FIG. 1, the cross ribs 10 are in 55 staggered and non-parallel relation to one another and 60 the inner end of each of the cross ribs terminates below the outer end of the next adjacent cross rib.

The segments 1 which, when placed end-to-end, form the grinding faces for the disk, are secured to the disk in the known manner by means of bolts extended through 65 the holes 12 formed in bosses 13 seen on the under side of the segment in FIG. 3.

When a grinding disk, composed of a plurality of the segments, is in rotative operation, the barriers or dams formed by the cross ribs 10, co-operate with similar ribs on the opposing disk to produce a scissoring action by which the grinding effect produced on the material is very substantially increased. These dams or barriers serve to

interrupt the radial flow of the material through the grooves 5 and they force the fibers of the material to be cut against the sides of the dams or barriers before the material can pass out through the grooves 5 in the segments. The relatively deep and wide grooves 6 aid in producing the desired grinding results, since the material to be ground enters between the disks at the center and it is initially rough or coarse ground by the tapering, widely spaced ribs 7 and fed therefrom into the flat, finer-grooved grinding area where the grinding of the material to the required degree takes place. By the use of segments constructed as above described, a much finer fiber is secured, the passage of slivers and chips is eliminated and other advantageous results attained.

In the embodiment of the invention shown in FIGS. 4 and 5, the ribs 4 extending transversely of the segment as described in connection with FIG. 1, are connected by cross ribs 15 which are substantially similar to the cross ribs 10, with the exception of the fact that each of the cross ribs 15 extends on a curved line or arm tangentially from the periphery of the segment and proceeds inwardly on such curved line to about the longitudinal center of the grinding area or flat face of the segment. These cross ribs form dams or barriers and operate substantially similarly to the cross ribs 10.

In the embodiment of FIGS. 4 and 5, the grooves 5, interrupted by the cross ribs 15, are not in end communication with the inner, wider grooves shown at 16. The rib portions 17 between which the wide grooves 16 are located, are somewhat sharply tapered from the point 18 to the inner edge of the segment. Other ribs shown at 19 are provided with recesses 20 and as seen in FIG. 5, such ribs have considerably less taper.

It should be noted that the grooves 16 and 20 are so terminated that they form staggered dams or barriers which serve to eliminate the accumulation of metal and the formation of ridges as explained in connection with FIG. 1.

In the embodiment shown in FIGS. 6 to 8 inclusive, the ribs 4, with the intervening spaces 5, are interrupted by cross ribs 25 which curve inwardly from the periphery 2 of the segment toward the longitudinal center of the same. In this arrangement, the cross ribs 25 are not continuous but are regularly interrupted by intervening grooves. That is to say, the cross ribs present the aspect of curved broken lines extending along the length of the segment. In operation this arrangement is substantially similar to the embodiments previously described.

By means of the designs of the several segments, it has been found possible to materially increase the width of the grinding zone, thereby keeping the material longer in such

zone and resulting in a better-refined fiber. Also by the employment of barriers or dams in the segments as herein described, the fiber cannot pass through the segments and leave the machine without being cut. In known types of segments there is usually heavy metal concentrated at the point where the feeding and rough grinding meets the flat or finer grinding zone. Such concentration of metal often results in the formation of a high ridge after a few days of operation. As these segments tend to wear out faster at their periphery due to the high velocity, the concentrated metal always wears down at a slower rate than do the grooves in the grinding zone. As a result, a V-shaped opening appears from the periphery of the segment to the above mentioned high ridge, which results in poor refining. In the segments of the present invention, the designs are such that the higher ridge is eliminated so that the grinding zone will tend to remain constant.

Having thus described several embodiments of the invention, it is obvious that the same is not to be restricted thereto, but is broad enough to cover all structures coming within the scope of the annexed claim.

What we claim is:

A grinding disk segment comprising an arcuate plate 25 having an outer flat grinding section which extends inwardly from the outer periphery of said plate and merges with an inner dished feeding section which extends outwardly from the inner periphery of said plate, a plurality of spaced oblique transversely extending flaring grooves 30 in said dished feeding section which progressively increase in width from said flat grinding section to the inner periphery of said plate, said flaring grooves communicating with aligned grooves of uniform width and depth in said flat grinding section which are of lesser depth and width than said flaring grooves and extend outwardly from said flaring grooves to the outer periphery of said plate, and a plurality of spaced cross rib means which extend angularly across said flat grinding section from the outer periphery of said plate and terminate radially inwardly from the said outer periphery with the inner end of each cross rib means being disposed in radial alignment with the outer end of the next succeeding cross rib means, each of said cross rib means intersecting a plurality of said contiguous aligned grooves.
